UNITED STATES PATENT OFFICE.

LLOYD W. BUCHENAU AND STEPHEN N. BLEWETT, OF STOCKTON, CALIFORNIA.

DESIGN FOR A COMBINED GUM AND PACKAGE-CONFECTION CASE.

Application filed April 16, 1928. Serial No. 26,355. Term of patent 14 years.

To all whom it may concern:

Be it known that we, LLOYD W. BUCHENAU and STEPHEN N. BLEWETT, citizens of the United States, residing at Stockton, in the county of San Joaquin and State of California, have invented a new, original, and ornamental Design for a Combined Gum and Package-Confection Case, of which the following is a specification, reference being had to the accompanying drawing, forming part thereof, in which—

Fig. 1 is a perspective view of a combined gum and package-confection case showing our new design.

Fig. 2 is a top plan view of the case.

We claim:—

The ornamental design for a combined gum and package-confection case, as shown.

LLOYD W. BUCHENAU.
STEPHEN N. BLEWETT.
